Attorney

UNITED STATES PATENT OFFICE.

THOMAS R. McDONALD, OF COLUMBUS, OHIO.

CIGARETTE CASE FOR BATHERS.

Application filed June 9, 1926, Serial No. 114,747. Renewed March 22, 1928.

This invention relates to cigarette cases specifically adapted for use by bathers in order that the cigarettes and matches may be carried into the water without any liability of the same becoming damaged by water or moisture.

The primary object of the invention is to provide a cigarette case of the above mentioned character that is extremely simple of construction, inexpensive of manufacture, and of such a nature as not to become readily broken even though subjected to rough usage by the bather.

Other objects will become apparent as the nature of the invention is better understood, the same comprising the novel form, combination, and arrangement of parts herein-after more fully described, shown in the accompanying drawing and claimed.

In the accompanying drawing wherein like reference characters indicate like parts throughout the several views:

Figure 1 is a detail longitudinal section of a bather's cigarette case constructed in accordance with the present invention, the dotted lines disclosing the lid of the case when removed from the body and further disclosing the cigarette and match receptacle in outwardly swung position with respect to the case body in order that proper access may be had to the cigarettes and matches.

Figure 2 is an inner side elevation of the case lid, and

Figure 3 is a plan view of the case when the lid is removed therefrom.

Now having particular reference to the drawing, my novel cigarette case constitutes the provision of a circular body 5 open at one side and rabbeted and threaded externally at said open side for receiving the interiorly threaded skirt of a screw type lid 6. Said body 5 and lid 6 are of some suitable water proof material preferably hard rubber or some other suitable material.

Upon the inner side of the lid 6 is a mirror 7 and a comb 8' which is necessarily of arcuate formation as more clearly disclosed in Figure 2.

Disposed within the body 5 of the case is a substantially rectangular shaped cigarette package receptacle 8, the opposite side walls of which are formed with vertical pockets 9—9 preferably for the reception of matches, the upper end of the receptacle being open and provided with a hinged lid 10, the ends of which extend over the upper open ends

of said match compartments as clearly disclosed in Figure 3.

The lower ends of the compartments 9—9 terminate short of the bottom wall of the receptacle 8 while the length of the receptacle is such as to permit the same to be disposed entirely within the case body so that the lid 6 may be disposed thereon. The rim of the case body 5 is of plane formation directly beneath the cigarette receptacle as indicated by the reference character 11 in Figure 3 so as to permit the bottom wall of the receptacle to rest flush thereon, the front side of this plane area being beveled so as to provide an inclined surface 12 at the open side of the body, Figure 1. The bottom wall of the cigarette package receptacle 8 is formed adjacent opposite ends thereof with depending ears 13—13 that are arranged within notches that are formed in the plane area of the body rim and through registering openings in which passes a pivot pin 14 embedded within the material forming the body directly beneath the surface of the plane area of the rim in order that the receptacle may be swung outwardly of the body to the dotted line position disclosed in Figure 1, thus affording access to the cigarettes and matches therein, the beveled area 12 of said plane surface permitting such a swinging action of the receptacle.

The back wall of the case body 5 is formed upon its outer side with an elongated bail 15 in order that the body belt of the bathing suit may be disposed therethrough, thus supporting the case upon the body of the bather. Other means may however be provided for facilitating the attachment of the case to the suit of the bather, the means disclosed merely serving to generally illustrate the fact that the case is to be attached directly to the suit of the bather, and this in such a manner as to maintain the cigarette and match receptacle in generally vertical position when so attached. Furthermore, the body 5 and lid 6 may be interconnected by a chain length 16 for preventing the loss of the lid when detached from the body of the case.

It will thus be seen that I have provided a highly novel, simple, and efficient form of bather's cigarette case that is well adapted for all the purposes heretofore designated, and even though I have herein shown and described the invention as consisting of certain detail structural elements it is nevertheless

less to be understood that minor changes may be made therein without effecting the spirit and scope of the appended claim.

Having thus described the invention, what I claim as new and desire to secure by Letters Patent is:—

In a structure of the class described, an outer casing comprising a hollow body open on one side, a removable cover for said open side, a second casing located within said

outer casing and having a centrally arranged pivotal connection with an adjacent wall of said outer casing, said wall being beveled on one side of the pivotal connection to permit said inner casing to be swung outwardly a limited distance when the aforesaid cover is removed. 15

In testimony whereof I affix my signature.

THOMAS R. McDONALD.
